UNITED STATES PATENT OFFICE.

JOHN NICHOLSON, OF CHICAGO, ILLINOIS, ASSIGNOR, BY DIRECT AND MESNE ASSIGNMENTS, TO THE NICHOLSON FURNACE COMPANY, OF CHICAGO, ILLINOIS, A CORPORATION OF ILLINOIS.

GRATE.

1,122,216.

Specification of Letters Patent. Patented Dec. 22, 1914.

Application filed October 28, 1912. Serial No. 726,027.

To all whom it may concern:

Be it known that I, JOHN NICHOLSON, a citizen of the United States, residing at Chicago, county of Cook, and State of Illinois, have invented a certain new and useful Improvement in Grates to be Used in Connection with Forced-Draft Furnaces.

Devices of this character with which I am familiar are subject to numerous objections among which might be noted that stratified furnace conditions in one part of the furnace chamber which contains a large percentage of distilled volatile matter, while another part contains the product of rapid combustion and still another part will admit the major part of the air to pass through a nearly burnt out fuel bed and around the grates, the air not reaching a sufficiently high temperature to ignite the combustible gases, due to the fact that it is not forced through the hot part of the fire bed.

Other systems are confined to the use of screened coal and also to the use of non-caking coals or in the event of the use of a caking coal, there is a very considerable loss of unburnt carbon. Any accident results in the necessity to close down the entire plant to permit movement of the grates. The efficient operation of the grates is also expensive. Underfeed and other stokers are objectionable due to the fact that they are confined to the use of screenings or coal with a low percentage of ash, which will not fuse at a low temperature. They are liable to have their parts burnt out if the fuel bed burns low and they are also compelled to close down in case of accident. There is no provision for proper supply and distribution of the incoming air. Hollow grate bars which are designed to handle forced draft with which I am familiar have been subject to the objection that there is a constant danger of a leakage of air, due to the warping of the bars, and there is also the liability for them to become clogged with ash, owing to improper air distribution.

My invention has for its object to avoid the above objections and to provide a grate which is designed to be used in connection with a closed ash pit and which will permit of the use in the furnace of a large volume of air at a low pressure and to construct the same so as to prevent the possibility of the ashes at any time preventing the free passage of the air and to provide an arrange-

ment, which will effect the distribution of the air to each bar and to each outlet in top of the grate so that there will be no tendency for the air to pass through the thin portion of the fire; and has for its further object to provide means for preventing the leakage of air and to locate the said means so that it will not be effected by the fire; and has for its further object to form the openings leading from the bars to the fire of such shape that a gyrating movement will be imparted to the entering air, thereby insuring its coming in contact with all of the surrounding coal; and has for its further object to provide a construction which will effectually prevent a larger amount of the air from entering the furnace through openings between or around the ends or sides of the grate bars and to provide a grate bar, the area and intake of whose outlets, will be in the same proportion for all lengths of grates.

My means of accomplishing the foregoing may be more readily understood by having reference to the accompanying drawings, which are hereunto annexed and are a part of this specification, in which:

Figure 1 is a longitudinal section of a part of a furnace, showing my improvement being used in connection therewith. Fig. 2 is a top or plan view of one of the bars. Fig. 3 is a side elevation, part of the side wall being broken away to show the interior construction. Fig. 4 is a cross section taken on line $x-x$ in Fig. 2. Fig. 5 is an enlarged fragmentary detail view, showing the means for imparting the gyrating motion to the incoming air prior to its entrance to the coals.

Similar reference numerals refer to similar parts throughout the entire description.

As shown in the drawings, the grate consists of a plurality of grate bars 1, which are provided with inwardly tapering side walls 2, which latter are provided with longitudinal flanges 3. When the bars are placed in position, an opening is formed which is to be filled with cement, as 4, of suitable composition to resist heat. It will be apparent that this body of cement located as it is so far below the fire and being constantly in contact with the incoming cool air will not be injuriously affected by the action of the heat, while any leakage of air between the grate bars is absolutely prevented.

The side walls are tapered inwardly until

they form a rectangular opening 5 for the admission of the air. This prevents the entrance of an excess of air into the grate bar, which is then permitted to expand into the 5 space 6 from which it escapes through a plurality of openings 7, which are tapered so as to bring the air down to a jet. They are also radially oblique, thus imparting a 10 gyrating movement as it enters the furnace, with the result that it insures the incoming air reaching every part of the fire and also retards its passage through the bed of the 15 fire.

It will be apparent from the foregoing 15 that any ashes which may fall through the openings 7 will have an unobstructed passage down into the pit 8, and can not under any circumstances clog the openings.

This construction secures a perfect distribution of the air throughout the fire and a 20 consequent increase in efficiency. Where it is employed I am able to use any kind of coal and to greatly increase the efficiency of the furnace.

25 The operation of the device is as follows: The air will enter the ash pit 8 through the opening 9 formed in the wall 10 of the furnace, as indicated by the arrows enter the grate bars through the opening 5 where it 30 is expanded in the chamber 6, whence it passes out through the openings 7 into the furnace; the air having a constant rotary motion results in its being thoroughly heated and distributed throughout the entire fire 35 bed with the desirable result as above set out.

Having described my invention, what I regard as new and desire to secure by Letters Patent is:—

40 1. In a forced draft furnace, a plurality of hollow grate bars having a top and end walls and downwardly and inwardly tapering side walls, the latter being provided with outwardly extending longitudinal flanges, there being a narrow rectangular opening between the side walls, the top wall having a plurality of jet openings in the top wall so shaped as to impart a whirl to the air as it enters the fire box, for the 45 purpose set forth, substantially as described.

50 2. In a forced draft furnace, a plurality of hollow grate bars having end walls and downwardly and inwardly tapering side walls, the latter being provided with outwardly extending longitudinal flanges, a 55 filler of suitable heat resisting material in-

termediate the tapered portion of the side walls and resting on the flanges, there being a narrow rectangular opening between the side walls, the top wall having a plurality of jet openings so shaped as to impart a whirl to the air as it enters the fire box, for the purpose set forth, substantially as described.

3. A hollow grate bar for forced draft 65 furnaces formed with a top and downwardly and inwardly tapering side walls, said top wall having a plurality of slots therein arranged in circular relation, and a plurality of openings extending in a radially oblique direction to said circular slots, whereby the air entering is caused to assume a gyrating motion, said radially oblique openings being located within said 70 arc-shaped openings, the walls of the radially oblique openings being flared downwardly so as to cause the air to enter in a 75 jet for the purpose set forth substantially as described.

4. In a forced draft furnace, a plurality 80 of hollow grate bars having a top and end walls and inwardly tapering side walls, the latter being provided with outwardly extending longitudinal flanges, a filler of suitable heat resisting material intermediate the 85 tapered portion of the side walls and resting on the flanges, there being a narrow rectangular opening between the side walls, the top wall having a plurality of jet openings so shaped as to impart a whirl to the 90 air as it enters the fire box and means to protect said filler from excessive heat, for the purpose set forth, substantially as described.

5. A rectangular hollow grate bar for 95 forced draft furnaces the top wall of which is provided with a series of openings, each series being arranged in circular relation and comprising a plurality of arc shaped slots the walls of which flare downwardly 100 and a plurality of radially oblique slots arranged within said arc shaped slots, the walls of said slots flaring downwardly, said radially oblique slots operating to impart a gyrating motion to the entering air. 105

In witness whereof I have signed the foregoing specification.

JOHN NICHOLSON.
